UNITED STATES PATENT OFFICE

2,459,517

VENETIAN BLIND

Roy E. Gearhart, Kansas City, Mo.

Application September 4, 1944, Serial No. 552,693

8 Claims. (Cl. 160—115)

1

This invention relates to improvements in Venetian blinds and has particular reference to a Venetian blind wherein a group of slats may be tilted independently of the position of tilt of the remaining slats of the blind.

The principal object of the invention is the provision of a Venetian blind having means whereby all the slats below a predetermined intermediate slat may be tilted in either direction independently of the angle of inclination of the slats above said intermediate slat.

Another object of the present invention is the provision of a blind construction including a plurality of slats supported in vertical spaced apart relation on a pair of ladder tapes having manually controlled means for simultaneously tilting all of the slats in the same general direction and provided with auxiliary tilting means whereby predetermined groups of said slats may be independently tilted.

Other objects are simplicity and economy of construction, ease and efficiency of operation and adaptability for use with the standard Venetian blind now in general use.

With these objects in view as well as other objects which will appear during the course of the specification, reference will now be had to the drawing wherein:

Fig. 1 is an inside elevational view of a Venetian blind mounted in a window frame embodying this invention.

Fig. 2 is an enlarged, foreshortened, sectional view taken on line II—II of Fig. 1 with all the slats shown in the horizontal position in solid lines and a lower group of the slats shown moved to the substantially closed position in dotted lines.

Fig. 3 is an enlarged, sectional view taken on line III—III of Fig. 2.

Fig. 4 is a perspective view of the adjustable tape clamp.

Fig. 5 is an elevation of the face of the clamp shown in Fig. 4.

Fig. 6 is a plan view of the head bar.

Fig. 7 is a sectional view foreshortened and taken on line VII—VII of Fig. 2.

Fig. 8 is an enlarged elevational view partly broken away of the slat tilting mechanism.

Fig. 9 is an enlarged sectional view of the lifting cord pulley and brake.

Fig. 10 is an enlarged sectional view of the auxiliary tilting cord pulley and brake mechanism.

Fig. 11 is a sectional view taken on line XI—XI of Fig. 10.

Fig. 12 is a sectional view similar to Fig. 2 with

both of the auxiliary tilting cords with their attaching clamps secured to the same side of the slats.

Fig. 13 is a diagrammatic view of the operating cord system.

Fig. 14 is a modified form of the Venetian blind shown in sectional view similar to Fig. 2.

Fig. 15 is a sectional view taken on line XV—XV of Fig. 14 with the slat foreshortened.

Fig. 16 is a plan view of the head bar shown in Fig. 14.

Fig. 17 is a sectional view similar to Fig. 2 of a further modified form of the blind wherein the auxiliary tilting cords are outside the blind proper.

Fig. 18 is an elevational view partly broken away of the upper portion of the blind mechanism shown in Fig. 17.

Throughout the several views like reference characters refer to similar parts and the numeral

20 designates a window frame carrying lower sash 22 and upper sash 24. The particular type of window structure on which this Venetian blind is used is immaterial; however, it is particularly suitable for use where it is desired to position some of the slats in one position while other slats are in another position. This variation in the position of the different groups of slats is found convenient for obtaining privacy, lighting and ventilation.

The head bar 26 is secured adjacent the top of the window frame by means of suitable side brackets 28 which are secured to the window frame in any suitable manner. This head bar is rigidly secured and serves as a support for the Venetian blind. A tilt bar 30 positioned in spaced relation beneath the head bar 26 is pivoted on its longitudinal axis. One end of said tilt bar is provided with a pivot 32 which is mounted in bearing 34 depending from and rigidly secured to the head bar 26 by means of screws 38. The other end of tilt bar 30 is provided with a pin 40 which is flattened to extend through an axial slot formed through the worm gear 42 for rotation therewith. This worm gear is mounted in a metal housing 44 provided with a bearing 46 in which the shaft 48 carrying worm 50 is mounted. This worm 50 is in operative engagement with worm gear 42 and is driven by a sheave wheel 52 which receives the drive cord 54. Radial ribs 56 in the inner face of the sheave wheel serve to cause a gripping action against the cord 54 thus preventing slippage of the cord relative to the sheave wheel. A pair of ladder tapes 58 and 60 extend downwardly from the tilt bar 30 and each comprises side tapes 61 and 63 provided with

cross tapes 62 on which a series of slats 64 are supported. The lower extremities of the ladders 58 and 60 are securely attached by means of fasteners 66 to a foot bar 68 which is maintained in parallel relation with the cross tapes. Each of the slats 64 is slotted at 70 between the side tapes 70 in the series of slats adjacent the respective ladder tapes are in vertical alignment and are adapted to receive a lifting or collapsing cord 72 which is secured at its lower end by knot 74 to the foot bar 68. This collapsing cord extends vertically over a pulley 82 which is rotatively mounted in housing 84 which in turn is secured by screws 86 to the head bar. Cord 72 then extends horizontally in groove 80 formed in the head bar 26 thence over pulley 76 pivotally mounted in head bar 26 by means of pin 78. The free end extremity of cord 72 extends downwardly to a convenient point so that the operator may grasp the cord to raise or lower the blind. A collapsing cord 88 similar to cord 72 and operative therewith passes over the sheave 82 thence over sheave 90, also rotatively mounted in head bar 26, thence downwardly between the side tapes of ladder 60. A clamp member 81 pivoted at 83 in housing 84 is adapted to normally rest against stop pin 85 so that the cords 72 and 88 may freely move over the pulley 76. However, when it is desired to secure the blind in a raised position the operator moves the cords to engage the clamp member to move it to the cord securing position shown in Fig. 9. It will be noted that these two cords 72 and 88 are clamped together at 81 so as to maintain them in proper relative relation whereby the slats of the blind will normally be maintained in parallel relation. It is obvious that the Venetian blind just described is the type now in general use and by operating the worm gear mechanism the tilt bar 30 may be moved to tilt all of the slats simultaneously in the same direction and through the same angle.

Since the principal object of the present invention is to provide means whereby a predetermined group of the slats may be tilted in one direction while another group is tilted relative thereto, the following tilting mechanism is provided.

Operating cords 92 and 94 extend upwardly over pulleys 96 and 98 respectively and are each bifurcated at 100 to present tilting cords 102 and 104. Tilting cords 102 of cords 92 and 94 pass over pulley 76, thence downwardly through openings 70 in slats 64 to respectively engage clamps 106 and 108 at opposite sides of the blind. The other set of tilting cords 104 of cords 92 and 94, extend over the sheave 90, thence downwardly to respectively engage clamps 110 and 112. Clamps 106 and 110 are secured to the inside of the blind to side tapes 61 of the ladder tapes 58 and 60 respectively, and clamps 108 and 112 are secured respectively to the outside tapes 63 of the ladder tapes 58 and 60 respectively. When so positioned with the tilting cords 102 and 104 of operating cord 92 attached in substantially horizontal alignment to the two inside tapes of the ladder tapes 58 and 60, by pulling downwardly on said operating cord the slats below the point of attachment may be tilted upwardly at the inside of the blind without interfering with the angle of tilt of the slats thereabove.

The clamps 106, 108, 110 and 112 are identical and are shown in detail in Figs. 3, 4 and 5. A channel member 113 having rebent ends 114 and 116 is perforated at its opposite ends at 118 and

120 to receive the slide bar 122. This slide bar is reduced at 124 to extend through perforation 120 and has an outturned portion 126 by means of which the bar may be manipulated. The other end of the bar is provided with a reduced tongue 128 which is adapted to be received through opening 118. The inner wall of channel 113 is roughened at 130 so that when the tape ladder member is positioned thereagainst and the bar 122 is moved to the securing position as shown in Fig. 3, the tape will be held against movement relative to the clamp. It will be noted that this clamp member is easily adjusted so that it may be positioned at any desired slat of the series thus making it possible to position them to tilt any desired lower group of slats. Furthermore, the pair of clamps 106 and 110 and the pair of clamps 108 and 112 may be positioned at relatively different vertical levels so that a lower group of slats may be adjusted relative to the slats thereabove in one direction or a larger lower group may be adjusted in the other direction or if the lower group has been previously adjusted then those slats thereabove controlled by the other tilting cord may be tilted in the opposite direction. The channel member 113 has a hook member 115 to which the tilting cord is attached.

The pulleys 96 and 98 are rotatably mounted on shaft 132 which is secured in housing 134. Screw 136 serves to secure the housing to the head bar 26. Partition 138 serves to separate the pulleys 96 and 98 and to form separate compartments for the cords 92 and 94. Each compartment is provided with an independently operable clamp 140 pivoted at 142 and provided with a stop pin 144 to limit its downward movement. When clamp 140 is resting against the pin 144 the operating cord is free to pass through the housing in either direction.

Referring to Fig. 12 it will be noted that the blind structure is similar to that shown in Fig. 2 and that the only change is the point of attachment of the tilting cords 102 and 104. It will be observed that both of the cords 102 are attached to the side tape 61 of the ladder tape 58 so that they are vertically spaced apart to control different groups of slats 64. Clamp 106 is positioned above clamp 108 so that when clamp 108 is raised by operating the cord all slats therebelow will be tilted. Likewise, when the slats are in the position shown, a vertical adjustment of clamp 106 will tilt all of the slats therebelow. Tilting cords 104 are likewise positioned relative to ladder tape 60 to operate in like manner to cords 102. When the slats below 108 have been tilted, it is evident that the group of slats controlled by clamp 106 thereabove can be tilted in like direction as the slats therebelow without interfering with the position of the slats thereabove and therebelow.

Reference will now be had to the modified form shown in Figs. 17 and 18.

The general structure of the blind is of standard structure such as shown in the preferred form, with the same collapsing means and also the same general tilting means whereby all of the slats of the blind are tilted simultaneously in the same general direction. In this modified form the auxiliary slat tilting means is positioned entirely outside the blind structure so that it may be easily attached without removing the blind from the window casing.

The cords 92 and 94 pass over pulleys 96 and 98 mounted in a structure such as shown in Figs. 10 and 11 and are each divided to present a tilting cord 102 and 104. Brackets 150 and 152 se-

cured by means of screws 154 to the side of head bar 26 serve instead of the roller shown in the preferred form to receive the tilting cords 102 and 104. The tilting cords 102 and 104 of the operating cord 92 extend through the upper eyes of the members 150 and 152 and extend respectively to clamps 108 and 112 (not shown) secured to the tape ladders 58 and 60 to side tapes 61. The group of slats therebelow are therefore, controllable by operating the cord 92. The tilting cords 102 and 104 of the operating cord 94 extend through the lower eyes of members 150 and 152 and extend downwardly to respectively engage clamps 106 and 110 (not shown) secured in like horizontal position on ladders 58 and 60 to side tapes 61. The clamps 106 and 110 are spaced above clamps 108 and 112 to present a group of slats therebetween which are tiltable by operating cord 94. When all the slats are in the horizontal position as shown, the operator by pulling downwardly on operating cord 94, may tilt all the slats below clamp 106. Likewise, by operating cord 92, all the slats below clamp 108 will be tilted. Should the lower group be tilted by means of cord 92, it is quite apparent that the group between clamps 106 and 108 may then be tilted by operating cord 94. It will be noted that these auxiliary cords both operate to move to tilt the slats in one direction only. However, by operating the tilting bar 30 in the usual manner, various combinations of degrees of tilting of the slats of the various groups may be varied.

The modified form shown in Figs. 14, 15 and 16 contemplates the application of my auxiliary tilting means with a standard Venetian blind wherein the lifting or collapsing cords 72 and 88 are positioned to extend vertically through side notches 160 and 162 formed in opposite edges of slats 164 and longitudinally spaced apart to respectively register with tape ladders 58 and 60. Notches 166 are formed in the edge of the slats transversely opposite notches 160, also notches 168 are formed transversely opposite notches 162. Collapsing cord 72 is attached at its one end by means of staple 170 to the foot bar 172 and extends upwardly through the series of notches 160, thence over the roller 174 which is rotatably mounted in a notch 176 formed in the side of head plate 178. It then passes lengthwise of the head plate to pass over the roller 82, thence downwardly in like manner as shown in Fig. 13. The other collapsing cord 88 passes over the roller 180 which is rotatably mounted in notch 182 formed in the opposite edge of the head plate 178. Otherwise these collapsing cords are similar in construction to those shown in the preferred form.

The operating cords 92 and 94 each bifurcated to form tilting cords 102 and 104 are like the corresponding cords in the preferred form and in general operate in like manner. Tilting cords 102 and 104 of cords 92 and 94 are adapted to different groups of blind slats in opposite directions. Tilting cord 102 of cord 92 passes over pulley 184 rotatably mounted in slat notch 186, thence downwardly to engage clamp mounted on tape 61 of ladder tape 58. Likewise, tilting cord 104 of cord 92 passes over roller 180 thence downwardly to engage a clamp 110 (not shown) which is secured to side tape 61 of ladder tape 60. These clamps 106 and 110 are in horizontal alignment and when operated by cord 92 will raise the inner edges of the slats therebelow in like manner. The cord 94 and associated tilting cords 102 and 104 are similarly mounted as the

10 cords just described and are adapted to tilt different groups of slats in the opposite direction. Tilting cord 102 of cord 94 passes over roller 174 rotatably mounted in slat notch 176 and extends downwardly to engage clamp 108 which is secured to side tape 63 of ladder tape 58. Tilting cord 104 of cord 94 passes over roller 192 rotatably mounted in notch 194 formed in head plate 178 and extends downwardly to engage clamp 112 secured to side tape 63 of tape ladder 60.

15 It will be noted that the clamp 106 engages the side tape 61 above the point where clamp 108 engages a side tape 63 of ladder tape 58. When cord 92 is pulled downwardly, all of the slats when positioned as shown in Fig. 14 and disposed below clamp 106 will be tilted in the same direction. Likewise, when cord 94 is drawn downwardly all the slats below clamp 108 will be tilted in the opposite direction. It is quite evident that by properly operating the standard titling means, together with the auxiliary titling means just described, many variations in the position of the groups of slats may be obtained.

20 While several forms of construction and adaptation of this invention have been shown, however, the forms are very similar and simply show different hook-ups and adaptations for different types of Venetian blinds now on the market, the principal object being to provide means independent of the present blind titling means whereby a group or groups of slats intermediate the top and bottom of the blind may be independently or collectively tilted in the same or in different directions. When using the clamps for engaging the side tapes of the ladder tapes the points of attachment may be easily varied vertically and from one side tape to the other without altering the construction of the auxiliary titling means. Many relative positions of the slats and groups of slats might be had without any alteration in the general construction of the titling apparatus.

25 45 Having thus described the invention, what I claim as new and desire to be secured by Letters Patent is:

1. In a Venetian blind construction including a plurality of slats supported in vertically spaced relation on a pair of ladder tapes and having manually controlled means for simultaneously tilting all of the slats in the same direction, and manually controlled means including cords extending through the upper slats and attached to the inner sides of said ladder tapes adjacent the slat below the lowest slat through which they pass and operable whereby a lower group of the slats are independently tiltable.

2. In a Venetian blind construction including a plurality of slats supported in vertically spaced relation on a pair of ladder tapes and having manually controlled means for simultaneously tilting all of the slats in the same direction, manually controlled means operable to tilt a lower group of the slats in one general direction, and another manually controlled means operable to tilt an intermediate group of the slats in the opposite general direction.

3. In a Venetian blind construction including a plurality of slats supported in vertically spaced relation on a pair of ladder tapes and having manually controlled means for simultaneously tilting all of the slats in the same direction, manually controlled means operable to tilt a lower group of the slats in one general direc-

tion, and manually controlled means operable whereby an intermediate group of the slats are tiltable to any desired degree in the opposite general direction independently of the slats thereabove.

4. In a Venetian blind construction including a plurality of slats freely supported on a pair of ladder tapes and having means for simultaneously tilting all of said slats in the same direction; means including a pair of cords secured respectively to the side tapes of one of said ladder tapes at opposite sides of one of the intermediate slats and extending upwardly over bearing members whereby when said cords are operated all the slats below said point of attachment may be adjusted to any desired tilting angle independently of the tilting angle of the slats positioned thereabove.

5. In a Venetian blind construction including a plurality of slats supported on a pair of ladder tapes and having means for simultaneously tilting all of said slats in the same direction; means including a pair of pliable members attached respectively to the side tapes of one of said ladder tapes adjacent one of the intermediate slats and extending upwardly to adjacent the top of said blind, and manually adjustable means operable to selectively move said pliable members whereby the slats below said intermediate slat are tilted to any desired angle independently of the angle of the slats above said intermediate slat.

6. In a Venetian blind construction including a plurality of slats supported on a pair of ladder tapes and having manually controlled means for simultaneously tilting all of said slats in the same direction; means including a pair of pliable members adjustably attached respectively to the side tapes of one of said ladder tapes adjacent one of the intermediate slats and extending upwardly to adjacent the top of said blind, and manually adjustable means operable to move said pliable members whereby the slats below said intermediate slat are tilted to any desired angle independently of the angle of the slats above said intermediate slat.

5 7. In a Venetian blind construction including a plurality of slats supported on a pair of ladder tapes and having manually controlled means for simultaneously tilting all of said slats in the same direction; means including a pair of pliable members adjustably attached respectively to the side tapes of one of said ladder tapes adjacent one of the intermediate slats and extending upwardly to adjacent the top of said blind, manually adjustable means operable to move said pliable members whereby the slats below said intermediate slat are tilted to any desired angle independently of the angle of the slats above said intermediate slat, and clamping means to secure said pliable members to the side tapes against accidental movement.

20 8. A Venetian blind construction comprising a pair of spaced ladder tapes each ladder tape comprising a pair of supporting tapes having cross tapes therebetween, a series of slats jointly supported by said ladder tapes and a pair of lifting cords providing means for effecting collapse of the Venetian blind structure, a rocker member operable to vary the angle of all of said slats, 25 a pair of cords secured at their one end at opposite sides of an intermediate slat to said ladder tapes and extending to the top of said blind whereby as said cords are operated the slats disposed below the slat adjacent said securing points may be tilted independently of the slats thereabove.
